CLAIM

The ornamental design for a container for an extension cord with ground fault interrupter, as shown and described.

DESCRIPTION

FIG. 1 is a top and front perspective view of a container for an extension cord with ground fault interrupter showing my new design in the open condition;

FIG. 2 is a side elevational view thereof;

FIG. 3 is a front elevational view thereof;

FIG. 4 is a rear elevational view thereof;

FIG. 5 is a top plan view thereof; and,

FIG. 6 is a bottom view thereof.

FIG. 1.

FIG. 3.

FIG. 2.

FIG. 5.

FIG. 4.

FIG. 6.
